2 Claims. (Cl. 114—5)

This invention relates to a device for mooring boats and similar vessels.

It is the object of this invention to provide a device which is simple and inexpensive in construction and which provides a stable device for the mooring of boats.

It is further an object of this invention to provide a device for mooring boats which has great flexibility with respect to the size and quantity of boats which may be conveniently and simply moored to the device.

These objects are attained in a device which comprises a jetty or foot-bridge which is attached to pilings and which is floatingly supported by transverse members or floats between which the vessels may be moored. The floats may be perpendicularly disposed with respect to the jetty or they may be positioned obliquely with respect to the jetty. The floats may extend out from either side of the jetty or both sides of the jetty. The floats may be variably spaced from one another and in this manner the mooring device can be adapted to the quantity and width of vessels to be moored. The floats may also extend further out one side of the jetty than the other side. In this manner vessels of varying length may be accommodated.

The floats themselves are of approximately semi-circular shape being flat and rigid on the top and circular on the bottom. Thus, in the event that the water freezes the floats will be forced upwardly by virtue of such configuration.

In the drawings:

FIG. 1 shows a view in perspective of the mooring device.

FIG. 2 shows a plan view of the device with the floats disposed perpendicular to the jetty.

FIG. 3 shows a plan view of the mooring device with the floats disposed obliquely to the jetty.

FIG. 4 shows a cross-section of the float taken along line 4—4 of FIG. 1.

In FIG. 1, jetty 1 is shown supported by floats 2 which in turn float on the surface of the water. Jetty 1 is provided with shackle 3 which engages pile 4 and ties the jetty thereto. The shackle 3 loosely engages pile 4 so that the jetty may rise or fall with the water level. Boats 5 may be moored along floats 2 and to jetty 1. Jetty 1 is comprised of planks 6 which rest on channel members or U-beams 7 to form a walking surface. U-beams 7 are provided with holes 8 situated at regular intervals. Shackles 9 which may be attached to the U-beams 7 through holes 8 by any conventional means secure floats 2 to the jetty 1. Holes 8 may also be used as points of attachment in mooring vessels to the jetty.

In FIG. 2 the floats 2 are spaced at varying distances from one another, e.g., *a* and *b* in FIG. 2. The extensions of the float to one side or the other of the jetty may also vary, e.g., *p* and *q*. In this manner the device may be simply and efficiently adapted to the breadth and length of the vessel to be moored.

2

In FIG. 3 the floats are disposed obliquely to the jetty so that the vessels 5 may be moored obliquely to the jetty. This arrangement may provide particular advantages in certain harbors where local conditions make it desirable to moor vessels at an oblique angle.

In FIG. 4 there is shown a cross-section of a float 2. The float 2 is made of a plastic core such as polystyrene foam 11 and a wooden top plate 12. The float is encased in a polyester sheathing 13 upon which a fixing plate 14 may be attached. Plate 14 is in turn provided with a mooring shackle 15.

While the invention disclosed herein is of particular value in tidal waters, it may also be used in nontidal waters including those having a constant level. Furthermore, it could be anchored rather than secured to pilings if such were desirable under local conditions.

While it has been suggested that polystyrene foam be used as a core material for the floats, it is readily apparent that many other similar materials may be used.

While a certain preferred embodiment of this invention has been herein shown and described, other modifications thereof will readily occur to those skilled in the art, and I therefore intend my invention to be limited only by the appended claims.

1 claim:

1. A device for mooring boats comprising
  - (a) a jetty comprising
    - (1) a pair of channel members having a plurality of spaced holes; and
    - (2) planks supported by said channel members;
  - (b) a plurality of floats disposed transversely of, and in supporting relation with, the jetty, each of said floats comprising
    - (1) a polystyrene core;
    - (2) a polyester sheathing;
    - (3) a flat top surface;
    - (4) an approximately semi-circular under surface;
    - (5) a mooring plate attached to the top surface; and
  - (c) a mooring shackle attached to the mooring plate;
  - (d) shackle means for attaching the floats to the jetty;
  - (e) means for anchoring the jetty including
    - (1) a pile; and
    - (2) shackle means attached to a channel member and loosely engaging the pile so as to permit the jetty to rise and fall with the level of the water.
2. A device for mooring boats comprising
  - (a) a plurality of elongated floats;
  - (b) an elongated jetty supported on said floats, said elongated jetty having a plurality of spaced holes arranged in first and second rows, said rows being parallel with one another;
  - (c) means connecting the jetty to each of said floats, said connecting means comprising:
    - (1) first and second shackle means for girding and holding in place each float with respect to the jetty;
    - (2) means for securing the first shackle means to the first row of spaced holes of the jetty; and
    - (3) means for securing the second shackle means to the second row of spaced holes of the jetty;
  - (d) said connecting means being adjustable to permit attachment of each float to the jetty at any of a

plurality of positions along the length of the float
and at any of the plurality of positions of the float
along the length of the jetty.
